UNITED STATES PATENT OFFICE.

JOSEPH WHITE, OF MIDDLESEX, NEW JERSEY; MINNIE E. WHITE ADMINISTRATRIX OF SAID JOSEPH WHITE, DECEASED, ASSIGNOR TO HALL PRINTING PRESS COMPANY, OF DUNELLEN, NEW JERSEY, A CORPORATION OF NEW JERSEY.

SHEET-SMOOTHING DEVICE.

Application filed October 11, 1919. Serial No. 330,024.

To all whom it may concern:

Be it known that I, JOSEPH WHITE, a citizen of the United States, residing at Middlesex, in the State of New Jersey, have 5 invented certain new and useful Improvements in Sheet-Smoothing Devices, of which the following is a specification.

My present invention relates to devices 10 particularly useful in printing presses by which a sheet may be smoothed out so as to be presented in an unwrinkled condition to a printing surface, and also so that such smoothing out may be accomplished at different stages in the progress of the sheet 15 through the press.

With these and other objects in view, my invention consists of certain novel features of construction, combination and arrangement of parts as will be more fully described and pointed out in the appended 20 claims.

In the drawings, Figure 1 is a sectional side elevation of an illustrative form of printing press in connection with which the 25 preferred form of my invention is shown, and Fig. 2 is a detail.

The corresponding parts are referred to both in the specification and in the drawings by similar reference characters.

30 The press which I have chosen for purposes of illustration is a multi-color offset press of the type illustrated in my prior Patent No. 1,214,485, in which there is an impression cylinder 10 and a pair of co- 35 operating printing or blanket cylinders 11 and 12 spaced apart a sufficient distance so that the sheet may be completely printed by the cylinder 11 before it reaches the cylinder 12, and a pair of form cylinders 40 13, 14 each cooperating with one of the printing cylinders 11, 12. The impression cylinder 10 is provided with the usual sheet grippers 15 and an impression surface 16.

The press is provided with a feed cylinder 45 17 having grippers 18 to take a sheet from a sheet support which, in the form illustrated, is made up of a series of tapes 19 which carry a sheet placed thereon, down to the feeding point of the cylinder 17 where the grippers 18 close thereon. The sheet is then 50 carried around to present the head thereof to the grippers 15 on the cylinder 10, and the sheet is carried by the grippers 15 past the printing cylinders 11 and 12 to a de-

livery mechanism of the usual type, shown 55 at the left of Figure 1. All of the cylinders are geared together and are rotating continuously in the illustrative type of machine. The mechanism so far described is old in the art and further description will therefore be unnecessary to those skilled in the 60 art.

Particularly in planographic printing, it is desirable that all of the minute wrinkles shall be smoothed out of the sheet before it 65 is printed, and when the sheet is to be printed in more than one color it is particularly desirable that the sheet be made to lie as flat as possible when the successive colors are imposed; otherwise the printing may be out 70 of register on some parts of the sheet where a wrinkle has changed the position of a part of the printing between successive impressions. To avoid this difficulty I provide devices which will pull the sheet rearwardly 75 after the head thereof has been engaged by the sheet grippers, and also preferably to give it a pull from the center outward in opposite directions by a pair of opposed lateral pulls, all of such pulls being directed 80 so that the sheet is stretched and smoothed over the cylinder surface.

As one simple form of device to smooth the sheet, I provide one or more rollers 20, 21 and 22, each of which preferably is covered with a fabric 20' so as to give a relatively rigid frictional contact with the sheet to exert a considerable pull thereon. Preferably, also, in order to provide opposed lateral pulls on the sheet, I apply such 85 fabric in the manner shown in Figure 2 in the form of spirals with the spirals on the opposite ends of the rollers of opposite hands. The roller 20 initially smooths the sheet while under the control of the grippers 18 and indeed, while also under the control 90 of the grippers 15 until the tail of the sheet passes the roller 20. The roller 21 further smooths the sheet on the surface 16 prior to the passage of the sheet beneath the printing cylinder 11. It will be understood that these rollers are set sufficiently tightly in contact with the surfaces of the cylinders and are themselves made to drag over the sheet, so that as the sheet is moved past 95 them these rollers tend to drag the sheet backward, and when provided with such a structure as that shown in Figure 2, to also 100 105

smooth the sheet outwardly from its center, thus effectually ironing out any wrinkles and causing the sheet to adhere tightly and smoothly to the cylinder surface.

6 If desired, I may also provide a smoothing device for the sheet to act thereon between the first and the second printing, and indeed, between any successive printings. When such a device is the roller 22 it will 10 be understood, of course, that the covering of such roller will be arranged so that preferably it does not run over any freshly printed surface.

As another form of sheet-stretching devices, and one which may be used either with the smoothing rollers or independently thereof, I have illustrated a mechanism by which the rearmost edge or tail of the sheet may be grasped and pulled rearwardly to 20 stretch the sheet. As an illustrative form of such mechanism I have shown grippers 25 on a shaft 26 mounted in a pair of arms 27 pivoted at 28 on the cylinder 10. The grippers 25 are controlled by a pair of segments 29, 30, the latter of which is pivoted at 31 on the arm 27, and is provided with a cam roller 32 contacting with a cam 33 attached to the side frame of the machine. The grippers 25 are closed by the spring 34.

30 The position of the arms 27 is controlled by a cam roller 35 running on a cam 36 also attached to the side frame and a spring 37.

In the machine illustrated, the grippers 25 are arranged to close on the tail of the 35 sheet after the sheet has begun to pass the printing cylinder 11, such closing being brought about by the roller 32 running down the cam 33. Shortly after this closing, the roller 35 runs down the cam 36 and this permits the spring 37, to move the arms 27 clockwise, and since the sheet is gripped at this time, this motion will pull or stretch the sheet on the surface 16. It is obvious that this stretching may take place at any time 45 after the head of the sheet has been grasped by the grippers 15, but, as shown in the drawings, this device will prevent the

wrinkling of the sheet which now sometimes arises because of the stretching action on the sheet due to the pulling thereof between the 50 impression surface 16 and the offset blanket on the printing cylinder 11. If this stretching is taken up as by the grippers 25, as soon as it arises, there will obviously be no wrinkling of the sheet, and the sheet will be 55 passed to the second impression in exactly the same condition in which it was printed by the cylinder 11. If, on the other hand, the sheet is permitted to stretch freely during the printing of the first impression 60 and is not thereafter restrained, it will return to its original condition as soon as released by the cylinder 11 and will therefore be presented to the cylinder 12 in a condition different from that in which it left the cylinder 11, thus causing out-of-register printing on some or all of the sheet. 65

While I have shown my invention in connection with an offset press in which it is particularly useful, it will be understood 70 that it may be used in connection with any form of press or indeed, with any machine in which it is desirable to smooth out a sheet prior to its being operated on.

I claim:

1. In a printing press, a cylinder having a sheet-taking device thereon adapted to engage the head of the sheet, and a fabric-covered roller adapted to press the sheet against the periphery of the cylinder as the sheet is 80 drawn past said roller, said fabric covering comprising a pair of opposed spiral strips arranged to exert lateral pulls on the sheet from its center toward its edges.

2. In a printing press, a cylinder having a sheet-taking device thereon adapted to engage the head of the sheet, and a fabric-covered roller adapted to press the sheet against the periphery of the cylinder as the sheet is drawn past said roller, said fabric being 90 arranged to exert lateral pulls on the sheet from its center toward its edges.

JOSEPH WHITE.
